(57) **CLAIM**

The ornamental design for a bin hanger, as shown and described.

DESCRIPTION

FIG. 1 is a perspective view of a bin hanger;
FIG. 2 is a front view of the bin hanger shown in FIG. 1;
FIG. 3 is a side view of the bin hanger shown in FIG. 1, the
opposite side of the bin hanger being the same as that shown
in FIG. 3;

FIG. 4 is a top view of the bin hanger shown in FIG. 1;
FIG. 5 is a bottom view of the bin hanger shown in FIG. 1;
and,

FIG. 6 is a back view of the bin hanger shown in FIG. 1.
The broken cut lines shown in the center of the bin hanger
and in the legs indicate indeterminate length and form no
part of the claimed design. The remainder of the broken lines
shown are for illustrative purposes only and form no part of
the claimed design.
